PULPSTONE

George N. Jeppson, Worcester, and Wallace L. Howe, West Boylston, Mass., assignors to Norton Company, Worcester, Mass., a corporation of Massachusetts

Application August 27, 1947, Serial No. 770,888

4 Claims. (Cl. 51—206.4)

1

The invention relates to pulpstones.

One object of the invention is to provide a simple and inexpensive pulpstone construction of the type having a plurality of abrasive blocks permanently secured to a rigid center. Another object of the invention is to provide a pulpstone that can be quickly manufactured. Another object of the invention is to provide a pulpstone construction which can be embodied in a pulpstone having very small blocks, thus reducing the internal heat stresses which tend to rupture larger blocks or segments, and also permitting the manufacture of a pulpstone having a small volume of abrasive, thereby reducing the cost of the stone. Another object of the invention is to provide a pulpstone construction altogether eliminating the use of holding bolts anchored to or embedded in the abrasive blocks, the use of which, up to the time of our invention, has been universal in practice with poured concrete center pulpstones and the use of which has involved a considerable item of expense in the manufacture of such pulpstones.

Other objects will be in part obvious or in part pointed out hereinafter.

The invention accordingly consists in the features of construction, combinations of elements and arrangements of parts, as will be exemplified in the structure to be hereinafter described, and the scope of the application of which will be indicated in the following claims.

In the accompanying drawings illustrating several of the many possible embodiments of the mechanical features of the invention,

Figure 1 is a fragmentary end elevation of a pulpstone constructed in accordance with the invention.

Figure 2 is a fragmentary view of the surface of the pulpstone of Figure 1.

Figure 3 is an axial sectional view of approximately one half of the pulpstone on an enlarged scale, the section being taken along the line 3—3 of Figure 2.

Figures 4, 5 and 6 are end elevations similar to Figure 1 showing modifications of the invention.

The type of pulpstone to which the invention relates is the concrete center pulpstone made by arranging a number of abrasive blocks, sometimes called segments, to form an exterior cylindrical surface, clamping the blocks together in such arrangement, locating a mold sleeve on the like inside of the blocks and then pouring concrete between the blocks and the mold sleeve to form the center. The hole left by the mold

2

sleeve is the mounting hole for the pulpstone or in some cases the sleeve around which the concrete is molded may remain as part of the pulpstone. Pulpstones of this general type are disclosed in U. S. Letters Patent to Jeppson No. 2,032,434 of March 3, 1936, U. S. Letters Patent to Larsson No. 2,074,114 of March 16, 1937, U. S. Letters Patent to Larsson No. 2,141,608 of December 27, 1938, U. S. Letters Patent to Howe & Washburn, No. 2,421,885 of June 10, 1947 and U. S. Letters Patent to Howe & Washburn, No. 2,421,886 of June 10, 1947. In these patents and elsewhere there has been disclosed the manner of assembling the abrasive blocks, separating them with sheets of filler material such as described in U. S. Letters Patent to Larsson No. 2,054,771, clamping the blocks together, placing the mold sleeve in position and locating a steel cage made of series of concentric hoops between the blocks and the mold sleeve and pouring the concrete to form the pulpstone center and, after the concrete has set, heating the entire assembly to bake or vulcanize the filler material. Therefore we will not describe such steps herein since they are now well known to the art and the present invention will be made quite clear by a description of the features of construction, combinations of elements and arrangements of parts.

Referring now to Figures 1, 2 and 3, we provide a plurality of abrasive blocks 10 which may be of the same shape and which shape is a feature of this invention. The abrasive may be of any suitable type such as fused alumina or silicon carbide bonded with vitrified bond all as explained in considerable detail in the above mentioned patents. Each block 10 has an outer surface 11 which is a segment of a cylinder. Each block 10 has side surfaces 12 which are preferably in planes neither parallel to nor perpendicular to the axis of the pulpstone. This shape is to preclude any series of joints from lying in a circle. The joints are filled with filler material 13 such as described in the Larsson Patent No. 2,054,771 and the filler material is non-abrasive so it is desired that this filler material shall not form a complete circle anywhere on the surface of the pulpstone in order that, as the pulpstone revolves, it shall give an abrading action over its whole length. Marginal blocks 10a, however, may have side surfaces 12a which are in planes perpendicular to the axis of the pulpstone.

Each block 10 further has a large end face 14 and a similar end face 15, each of said faces 14 and 15 lying substantially in radial planes of the

pulpstone. The inner surface 16 of each of the blocks 10 consists of a series of projections 17 separated by a series of grooves 18, both projections and grooves extending clear across the face 16 in an axial direction. Preferably the sides of the projections 17 are parallel and are perpendicular to the bottoms of the grooves 18. The projections 17 are in effect wide teeth. The tops of the projections or teeth 17 are substantially in a plane which plane is non-parallel to a plane tangent to the surface 11 of the particular block 10. The parallel sides of the projections or teeth 17 are at angles to radial planes of the pulpstone passing through any part of the parallel sides. When the concrete is poured to form the concrete center 20 it becomes keyed to the blocks 10. In other words no block 10 can be removed from the concrete center without breaking some of the concrete or projections 21 thereof which extend into the grooves 18.

An important feature of the present invention is that the blocks 10 are not only keyed to a greater or lesser extent to the concrete center 20, but they are also strongly held thereto by adhesive forces. The surfaces of the blocks 10 are porous and somewhat rough everywhere, owing to the fact that the blocks are made by mixing hard abrasive material with powdered ceramic bond, moulding and vitrifying, which results in a certain porosity of the blocks, which can be varied, but it is never zero. Surfaces of such bonded abrasive material are well adapted to being secured by an adhesive.

On the other hand, the adhesive strength of a concrete mix, such as a 1:1:1 mix, that is equal parts by weight of Portland cement, sand and trap rock, is not in itself sufficient. We have found that by greatly increasing the area of contact between the blocks and the concrete sufficient holding power can be developed to hold the blocks 10 in place. The 1:1:1 mix has high adhesive strength for concrete.

The construction described eliminates the use of the various types of holding bolts disclosed in the aforementioned patents, all of which types are expensive. For reinforcement of the center 20 we preferably provide a plurality of steel hoops 25, 26 and 27, the hoops 25 being of the largest diameter, the hoops 26 being of somewhat smaller diameter, and the hoops 27 being of the smallest diameter, all as is clearly apparent from a comparison of Figures 1 and 3. The sets of hoops 25, 26 and 27 are held together in the form of cages by means of spacing and supporting irons 30 as clearly shown in Figure 3. These cages lie within and reinforce the concrete center 20.

As further reinforcement we preferably provide U-shaped irons 31 having bent-over ends 32 which may be wired by wires 33 to the hoops 26 before the concrete is poured. The bent-over ends 32 are located close to the surfaces 14 of the blocks 10 and in the angle between said surfaces and the surfaces 16 to reinforce the concrete where it extends to the greatest radial distance. These U-shaped irons 31 measurably add to the strength of the pulpstone, but they are relatively inexpensive since no turning or threading operation need be performed upon them.

One feature of the pulpstone of Figures 1 to 3 is that if mounted for revolution in the direction of the arrow in Figure 1, the surfaces 14 of the blocks 10 projecting inwardly between the adjacent blocks form large driving surfaces to preclude destruction of the pulpstone from the high

torque involved when the grinding operation is heavy.

Modifications of the invention may be made as illustrated in Figure 4, 5 and 6 which we do not intend, however, to be limiting since other variations and modifications may be made.

Referring now to Figure 4, blocks 40 have, centrally located on their inside surfaces 41, a pair of projections 42 extending farthest inwardly and separated by a groove 43. Spaced from these projections 42 by grooves 44 are projections 45 extending not quite so far inwardly. Spaced from these projections 45 by grooves 46 are projections 47 which are stepped back still further and which lie adjacent to the faces 14a and 15a. In this construction there is some, but not a great deal of, interlocking between the concrete 20 and the blocks 40; however, there is a large area of contact for adhesion and there are many surfaces to absorb the driving torque. We have discovered that whereas too pronounced interlocking is apt to cause fracture of the concrete, attachment by extensive surfaces in adhesive engagement with the concrete does not cause fracture either of the concrete or of portions of the blocks under the torque load now customarily encountered in paper mills.

Referring to Figure 5 another modification is disclosed in which blocks 50 have inside surfaces 51 with single center projections 52 separated by grooves 53 from a pair of stepped back projections 54 which are separated by grooves 55 from a pair of further stepped back projections 56 leaving space for large concrete projections 57 between adjacent blocks. This construction also embodies all of the features above noted in that there is some interlocking, a great deal of surface area for adhesive attachment and many opposed radial surfaces for the driving torque.

The modification shown in Figure 6 is particularly desirable where a highly economical pulpstone is wanted and of low initial cost. The blocks 60 have inside faces 61 with projections 62 whose ends are in a plane separated by grooves 63 whose bottoms are in a plane and these planes are parallel to planes tangent to the outer surfaces 11 of the blocks 60 at the mid points thereof. Thus the pulpstone of Figure 6 can be used until almost all of the abrasive material has been worn away. The blocks 60 can be made as thin as desired in a radial direction. Some mills want a pulpstone of low initial cost even though the cost of grinding in terms of pulpstone wear is slightly higher than if they bought a more expensive stone in the first place. In the construction shown in Figure 6 there is some, but not very much, interlocking between the concrete center and the blocks 60, but there is a great deal of surface area for adhesive attachment. The stone of Figure 6 has radial driving areas formed by the sides of the projections or teeth 62 and the sides of the concrete teeth in the grooves 63, but not such great total area as in the case of the other embodiments of the invention.

The function of the various projections or teeth and grooves is largely to make indented surfaces to increase the surface area of contact between the abrasive blocks and the concrete center 20 to increase the holding force due to adhesion. Furthermore in the case of the pulpstone of Figures 1 to 3, the surfaces 14 are in adhesive engagement with the concrete center 20. The increase in the surface area by reason

of the indentation may be calculated on the assumption that the pulpstone ceases to be useful when the blocks have been worn down to expose some of the concrete center 20. Blocks which would leave no abrasive embedded in the concrete when the concrete first became exposed would be blocks having inner surfaces collectively forming a cylinder. The simplest approximation to such blocks would be blocks whose inner surfaces are planes forming chords of such cylinder. In each of the embodiments of the invention such chord planes can be measured. Since in the illustrative embodiments of the invention there are no indentations in an axial direction the areas of such chord planes are proportional to the chord lengths thereof. The ratio of the indented surface area of a block of Figure 1 to the chord plane area is therefore found by measuring the chord length at the deepest indentation and comparing it with the total length along the indentations. Thus in Figure 1 we measure from junction to junction of the blocks and find the chord length and then we measure the total length along the indentations of surface 16 plus the length of the surface 14 in contact with the concrete 20. The ratio of the chord length to the indentation length in Figure 1 is 3 to 7.1. Therefore the ratio of the chord surface to the indented surface is 3 to 7.1. In Figure 4 we measure the chord length across the bottoms of the grooves 46 and we measure the indented length following each projection and groove and the walls thereof. In Figure 4 the chord length is to the indented length as 2.8 to 6.7 and therefore the chord surface is to the indented surface as 2.8 to 6.7. Similarly in Figure 5 we find the chord area is to the indented area as 2.4 to 5. And in Figure 6 we find the chord area is to the indented area as 3.2 to 6. The smallest increase of the indented surface as compared with the chord surface is in the case of Figure 6 where 6 divided by 3.2 equals 1 $\frac{1}{8}$. We prefer that the ratio of indented surface area to chord surface area shall be at least 1 $\frac{1}{8}$. Thereby sufficient holding power is developed to hold the blocks in place. A higher factor than 1 $\frac{1}{8}$ is desirable but on the other hand it is desirable to leave as little of the abrasive blocks embedded in the concrete when the concrete is first exposed as is possible. Therefore modifications such as illustrated and others can be made of the invention to suit different requirements for pulpstones for conditions in different mills provided the above factor is at least 1 $\frac{1}{8}$.

Another feature of the invention is that the increase in surface area due to the indentation is achieved without forming any narrow necks either in the abrasive blocks or in the concrete. For example, the projections 57 of concrete in Figure 5 can be called dovetails but they definitely do not have narrow portions. The ends of these dovetails 57 are nearly as wide as the narrowest portions at the bases. Thus pulpstones according to the present invention rely for holding the blocks to the centers especially on the adhesion of concrete to vitrified abrasive material. There is preferably some interlocking between the concrete and the vitrified abrasive material. In all cases projections of concrete extend into depressions of vitrified abrasive material and projections of vitrified abrasive material extend into depressions of concrete. In all embodiments except that of Figure 6 there is considerable interlocking of such projections and depressions. But preferably there are no projec-

tions of concrete or abrasive having sections which have less than four-fifths of the area of the largest sections of such projections.

It will thus be seen that there has been provided by this invention a pulpstone in which the various objects hereinabove set forth together with many thoroughly practical advantages are successfully achieved. As many possible embodiments may be made of the above invention and as many changes might be made in the embodiments above set forth, it is to be understood that all matters hereinbefore set forth or shown in the accompanying drawings is to be interpreted as illustrative and not in a limiting sense.

15 We claim:

1. A pulpstone comprising a plurality of blocks of vitrified bonded abrasive material having an outer cylindrical surface, a concrete core in adhesive engagement with inner surfaces of said blocks, each inner surface of each block being indented where it is in contact with the concrete and the surface area of each block in adhesive engagement with the concrete having a ratio of at least one and seven-eighths to the area of a chord plane at the deepest indentation, reinforcing irons in the concrete core parts of which extend to a further radial distance than the innermost portions of the blocks, there being substantial interlocking of the concrete core with the
- 20 vitrified bonded abrasive blocks, there being projections of concrete extending into depressions in the vitrified abrasive material and projections of vitrified abrasive material extending into depressions in the concrete, but no projections of concrete or vitrified abrasive material having sections which have less area than four-fifths of the area of the largest sections of such projections, and at least one-third of the concrete being Portland cement.
- 25 2. A pulpstone comprising a plurality of blocks of vitrified bonded abrasive material having an outer cylindrical surface, a concrete core in adhesive engagement with inner surfaces of said blocks, each inner surface of each block being indented where it is in contact with the concrete and the surface area of each block in adhesive engagement with the concrete having a ratio of at least one and seven-eighths to the area of a chord plane at the deepest indentation, and at least one-third of the concrete being Portland cement.
- 30 3. A pulpstone comprising a plurality of blocks of vitrified bonded abrasive material having an outer cylindrical surface, a concrete core in adhesive engagement with inner surfaces of said blocks, each inner surface of each block being indented where it is in contact with the concrete and the surface area of each block in adhesive engagement with the concrete having a ratio of at least one and seven-eighths to the area of a chord plane at the deepest indentation, reinforcing irons in the concrete core parts of which extend to a further radial distance than the innermost portions of the blocks, and at least one-third of the concrete being Portland cement.
- 35 4. A pulpstone comprising a plurality of blocks of vitrified bonded abrasive material having an outer cylindrical surface, a concrete core in adhesive engagement with inner surfaces of said blocks, each inner surface of each block being indented where it is in contact with the concrete and the surface area of each block in adhesive engagement with the concrete having a ratio of at least one and seven-eighths to the area of a chord plane at the deepest indentation, there

being substantial interlocking of the concrete core with the vitrified bonded abrasive blocks, there being projections of concrete extending into depressions in the vitrified abrasive material and projections of vitrified abrasive material extending into depressions in the concrete, but no projections of concrete or vitrified abrasive material having sections which have less area than four-fifths of the area of the largest sections of such projections, and at least one-third of the concrete being Portland cement.
